Fig. 3. Inventor:

5 Henning Hedwall.

By his attorney, Paul S. Gooding.

UNITED STATES PATENT OFFICE.

HENNING HEDWALL, OF QUINCY, MASSACHUSETTS.

COLLAPSIBLE DOOR.

1,012,849.

Specification of Letters Patent. Patented Dec. 26, 1911.

Application filed January 20, 1911. Serial No. 603,627.

To all whom it may concern:

Be it known that I, HENNING HEDWALL, a subject of the King of Sweden, residing at Quincy, in the county of Norfolk and 5 State of Massachusetts, have invented new and useful Improvements in Collapsible Doors, of which the following is a specification.

This invention relates to improvements in 10 collapsible doors of that class in which the door proper is composed of a series of strips or sections hinged to each other on vertical axes, such as that which forms the subject matter of U. S. Letters Patent, No. 15 958,961, issued to me May 24, 1910, and the object is primarily to provide a door of this class which shall be automatic in its action, simple and practical in its construction and which shall operate in a reliable 20 manner without cramping or binding.

One feature relates to improved means for supporting and guiding the door.

Another feature relates to a means for 25 assuring the proper action of the sections in folding upon one another in entering the casing and unfolding preparatory to leaving the casing.

To these ends, my invention consists in the novel features of construction and in the 30 combination and arrangement of parts set forth in the following specification and particularly pointed out in the claims.

Referring to the drawings: Figure 1 is an 35 elevation of a door embodying my invention with its casing partly in section and the guides at top and bottom of the door partly in section. Fig. 2 is an enlarged plan section taken on line 2—2 of Fig. 1, showing the door in its closed position. Fig. 3 is a 40 plan section taken on line 2—2 of Fig. 1, showing the door in its open position. Fig. 4 is a detail plan section taken on line 4—4 of Fig. 1, showing the parts of the door in the position which they occupy after 45 the door has started to collapse. Fig. 5 is a detail sectional view taken on line 5—5 of Fig. 1, looking toward the left. Fig. 6 is a detail plan section taken on line 2—2 of Fig. 1, showing some of the hinged sections folded upon one another within the casing and illustrating the action of the guides which assure a proper action of the sections in folding upon one another in en-

tering the casing and unfolding preparatory to leaving the casing.

55

Like numerals refer to like parts throughout the several views of the drawings.

In the drawings, the numeral 10 designates generally the door proper which is composed of a series of sections of any desired number 11, 12, 13, 14, 15 and 16, said sections being hinged to each other upon hinges 17, 18, 19, 20 and 21, the hinges 17, 19 and 21 being located on one side of the door and the hinges 18 and 20 being located 60 on the opposite side of the door so as to assure the proper folding action of the sections one upon another. The several sections are preferably rabbeted into one another, as shown, so as to make the door 65 tight and also to increase its strength against any lateral pressure that may be brought to bear against it from either side.

The sections of which the door is composed are suspended from a suitable guide 75 track 22 in any suitable manner as by providing wheels 23 and 24 arranged to roll along the track 22, the former being journaled upon a suitable bracket 25 secured to the section 11 and the latter being journaled 80 upon a suitable bracket 26 secured to the section 16. The track 22 is preferably mounted in a suitable horizontal casing 27 provided in its under side with a slot 28 through which the sections of which the 85 door is composed extend. There is also preferably provided a vertical casing 29 having therein a chamber 30 to receive the several sections of the door when collapsed, said casing having a vertical slot 31 through 90 which said sections pass in entering and leaving said chamber. The track 22 extends into the upper portion of the chamber 30, as shown in Figs. 1 and 4, and the terminal portion of said track within said 95 chamber is provided with a laterally inclined offset portion 32 extending at an obtuse angle to the straight portion of the track. Preferably, the track 22 is provided with a suitable groove 33 in its upper side to 100 guide the wheels 23 and 24, this groove being preferably narrow along its straight portion and being preferably widened and made somewhat V-shaped at its offset portion 32, as shown in Fig. 5, so as to permit the wheel 24 to travel around the curve 105

of the laterally offset portion 32 and to allow the section 16 to swing into a position transverse to said offset portion of the track. Preferably, the track 22 is located directly 5 above the upper extremities of the hinged sections of the door so that the door is thereby prevented from lifting and the wheels from jumping off of said track. The track is preferably provided in its under side 10 with a groove 34 in its straight portion, in which groove the upper extremities of the hinged sections are guided and prevented from swinging one upon another. This groove, of course, terminates at the entrance 15 to the chamber 30 so that when the sections enter the chamber they may swing laterally upon their respective hinges. Preferably, the lower extremities of the hinged sections are guided by a suitable guide 35 which may 20 be either the floor or threshold provided with a groove 36 to receive the door and constituting lateral guides therefor. This guide may also be provided with a groove or slot 37 to receive a pin 38 projecting 25 from the bottom of the section 16. This slot will, of course, be laterally offset at an obtuse angle to the groove 36.

Located within the casing 29 are two converging lateral guides 39 and 40 which converge toward the slot 31 and are secured to said casing adjacent to said slot, these guides preferably consisting of springs adapted to yield laterally when engaged by the sections of the door. The guide 39 coöperates with 30 a projection 41 on the section 14 and the guide 40 coöperates with a similar projection 42 on the section 15. These guides constitute one of the important features of my invention and it will be understood that if 35 it were not for the provision of these guides the hinged sections in folding and unfolding would tend to swing too far one way or the other and would thus become inoperative. For example, referring to Fig. 5, it 40 will be observed that the projection 41 prevents the section 14 from swinging toward the left too far, it being evident that if it should swing too far toward the section 13 it would not unfold in its opening movement. In a similar manner, the projection 42 prevents the section 15 from swinging 45 too far and causing a like difficulty. These guides, moreover, constitute a sort of throat from which the sections issue as they fold 50 one upon another, as shown in Fig. 6, and they assure a positive, reliable and automatic folding and unfolding of the sections.

The section 11 may be provided with a suitable handle or handles 43 by means of 55 which the door may be operated. If desired, the door casing may be provided opposite the casing 29 with a vertical groove 44 to receive the left hand edge of the section 11.

One of the advantages possessed by the 65 door is that the sections, when folded one upon another, occupy but a very small amount of space and a comparatively small casing may be provided to receive them when collapsed. This is, of course, a distinct advantage where economy of space is necessary.

The door may be built of either wood or metal, as desired, and when built of metal is very serviceable and may serve as a fire 75 door or shutter.

Having thus described my invention, what I claim and desire by Letters Patent to secure is:

1. A collapsible door having, in combination, a series of sections hinged together on vertical axes, a guide track located above said sections, said track having a laterally inclined offset at one end thereof, and two wheels journaled on two of said sections respectively and arranged in rolling contact with said track.

2. A collapsible door having, in combination, a series of sections hinged together on vertical axes, means to support and guide 90 said sections including a guide having a laterally inclined offset at one end thereof, a casing provided with a vertical slot through which said sections may pass into said casing, and a pair of guides located in said 95 casing and converging toward said slot.

3. A collapsible door having, in combination a series of sections hinged together on vertical axes, means to support and guide said sections including a guide having a laterally inclined offset at one end thereof, a casing provided with a vertical slot through 100 which said sections may pass into said casing, and a pair of laterally yieldable guides located in said casing and converging to- 105 toward said slot.

4. A collapsible door having, in combination, a series of sections hinged together on vertical axes, means to support and guide said sections including a guide having a laterally inclined offset at one end thereof, a casing provided with a vertical slot through 110 which said sections may pass into said casing, and a pair of laterally resilient springs constituting guides located in said casing 115 converging toward said slot and secured to said casing adjacent to said slot.

5. A collapsible door having, in combination, a series of sections hinged together on vertical axes, means to support and guide 120 said sections including a guide having a laterally inclined offset at one end thereof, a casing provided with a vertical slot through which said sections may pass into said casing, and a pair of guides located in said 125 casing and converging toward said slot, the free end of one of said guides extending beyond the other.

6. A collapsible door having, in combination, a series of sections hinged together on vertical axes, means to support and guide said sections including a guide having a laterally inclined offset at one end thereof, a casing provided with a vertical slot through which said sections may pass into said casing, a pair of guides located in said casing and converging toward said slot, and means

projecting from a plurality of said sections 10 adapted to engage said guides.

In testimony whereof I have hereunto set my hand in presence of two subscribing witnesses.

HENNING HEDWALL.
